UNITED STATES PATENT OFFICE

WILLIAM H. ALSTON, OF SAN ANTONIO, TEXAS

DESIGN FOR A BARBECUE STAND

Application filed April 4, 1933. Serial No. 47,686. Term of patent 14 years.

To all whom it may concern:

Be it known that I, WILLIAM H. ALSTON, a citizen of the United States of America, residing at San Antonio, in the county of Bexar and State of Texas, have invented a new, original, and ornamental Design for a Barbecue Stand, of which the following is a specification, reference being had to the accompanying drawing, forming a part thereof.

I claim:

The ornamental design for a barbecue stand as shown.

WILLIAM H. ALSTON.
